(57) **CLAIM**

The ornamental design for a tin can, as shown and described.

DESCRIPTION

This design application has subject matter related to co-pending design applications numbers, 29/219,612, 29/219,614, 29/219,616, 29/219,615, 29/219,610.

FIG. 1 is a perspective view of a tin can showing our new design

FIG. 2 is a front elevational view thereof, wherein the rear and side elevational views are identical thereto;

FIG. 3 is a top view thereof; and,

FIG. 4 is a bottom view thereof.

The broken lines shown in the drawing disclosure are for illustrative purposes only and form no part of the claimed design.
